[57] CLAIM

The ornamental design for an outdoor weatherproof plate and closure combination, as shown and described.

DESCRIPTION

FIG. 1 is a front isometric view of an outdoor weatherproof plate and closure combination showing our new design;

FIG. 2 is a top plan view of FIG. 1;

FIG. 3 is a front elevational view of FIG. 1;

FIG. 4 is a side elevational view taken from the right of FIG. 1;

FIG. 5 is a rear elevational view of FIG. 1;

FIG. 6 is a bottom plan view of FIG. 1;

FIG. 7 is a front isometric view of a second embodiment of the design of FIG. 1;

FIG. 8 is a top plan view of FIG. 7;

FIG. 9 is a front elevational view of FIG. 7;

FIG. 10 is a side elevational view taken from the right of FIG. 7;

FIG. 11 is a rear elevational view of FIG. 7;

FIG. 12 is a bottom plan view of FIG. 7.
